UNITED STATES PATENT OFFICE.

GEORGE H. MINIER AND THADDEUS LOWE, OF SOUTH PASADENA, CALIFORNIA.

GAS-FURNACE.

1,032,695.

Specification of Letters Patent. Patented July 16, 1912.

Application filed August 27, 1910. Serial No. 579,331.

To all whom it may concern:

Be it known that we, GEORGE H. MINIER and THADDEUS LOWE, citizens of the United States, residing at South Pasadena, in the county of Los Angeles and State of California, have invented certain new and useful Improvements in Gas-Furnaces, of which the following is a specification, reference being had therein to the accompanying drawing.

10 This invention relates to gas furnaces and has for its object to provide an improved gas furnace which will be simple in construction and effective in operation.

The invention further has for its object 15 to provide an improved gas furnace by means of which all the products of combustion may be utilized to radiate heat.

Referring to the accompanying drawings:—Figure 1 is a front view in elevation 20 and vertical transverse section of the furnace. Fig. 2 is a front view of the furnace constructed in accordance with this invention. Fig. 3 is a side view in elevation and transverse vertical section on the line $y-y$ 25 of Fig. 2. Fig. 4 is a rear view of the furnace with the casing broken away. Fig. 5 is a plan view of the bottom of the furnace in cross section showing the burners.

The furnace constructed in accordance 30 with this invention consists of three main parts—the fire box, the drum or radiator, and the jacket or casing. The fire box 1 consists of a rectangular sheet iron box having secured to its under side an asbestos plate 2 to prevent the radiation of heat into the floor or foundation upon which the furnace rests and which supports the furnace in elevated position so as to permit the air to enter and ascend the air spaces surrounding 35 the drum. The fire box 1 is formed with an opening, the top of which opens into a drum 3 which consists of a rectangular sheet iron box having its sides and rear wall extending to the bottom of the fire box and secured 40 thereto, as shown by the rear wall 3' in Fig. 3. The front wall 4 of the drum terminates at its lower end at the top of the fire box, where it is connected with a transverse strip 5, the rear edge of which is packed 45 with a strip of asbestos 5', and the front edge of which is secured to a transverse front plate 6 forming the front of the fire box and terminating at a short distance 50 above the bottom of the fire box so as to form an opening 7 for the passage of air to the fire box and up through the drum.

The fire box is braced by means of diagonal braces 6'. Surrounding the drum and the fire box is a rectangular casing 8 of sheet metal which is spaced from the drum so as 50 to form vertical air spaces on each side thereof, said casing extending a little distance above the top of the drum so as to form air spaces at the top of the drum and casing. The casing 8 is suitably supported, 55 as, for example, by means of angle irons 9 connecting the casing with the drum. The top of the casing 8 is provided with vertical openings 10 for the escape of warm air from the casing into the room to be heated. 70

Suitable burners are provided which are located in the fire box and, as here shown, preferably consist of pipes 11 extending lengthwise of the fire box and secured at their rear end to the wall of the fire box 75 and at their front end to the depending plate 6, said pipes being provided with sets of holes 12 for the escape of gas, which is controlled by needle valves and air mixers. The front ends of the pipes 11 are provided 80 with pipe extensions 13 which connect with depending branch pipes 14 connected with a main gas supply pipe 15 leading to a supply tank. The needle valves and air mixers of the burner pipes 11 are controlled by 85 suitable handles 16 at the ends of the branch pipes 13 and the main gas supply pipe 15 is provided with a controlling valve 17. The fire box is also provided with a lighter burner which consists of a curved perforated 90 pipe 18 with elongated arms 18' and connected by a coupling 18² to a branch pipe 18³ with a valve 19 for controlling the needle valves in the burner 18. When the burner pipes 11 are lighted by the lighting 95 burner 18, the lighting burner is turned out and the burner pipes 11 supply the heat to the furnace. The burner pipes 11 are so placed and the apertures are so located that the flames of the burning gas do not come 100 directly in contact with the sides of the fire box and in this way the life of the iron in the fire box is prolonged. Gases, smoke, fumes, steam, and other products of combustion pass up through the fire box 105 into the radiator or drum where their upward progress is arrested by baffle plates located in said drum.

The casing 8 is preferably constructed of galvanized iron and has a lining 20 of 110 bright tin situated about three-fourths of an inch from the casing and forming a

narrow chamber 20' just inside the casing which is open at the top and bottom and through which a current of air is at all times passing, which current of air prevents 5 the radiation of heat from the casing. This current of air is admitted through an opening 21 in the front wall of the casing just above the front plate 6 of the fire box, said air also passing through an opening 22 in 10 the bottom of the lining 20 into the air space located between the lining 20 and the walls of the drum 3. The lining 20 is supported by means of brackets 23 between the lining 20 and the walls of the drum 3. The 15 baffle plates 24 consist of plates formed of sheet metal and parallel with each other and spaced one above another and secured at their edges by means of brackets 25 to opposite sides of the drum 3. These baffle 20 plates 24 are so mounted on the brackets 25 as to leave a space between the edges of the baffle plates 24 and the sides of the drum 3. The baffle plates are so located in respect to the sides of the drum 3 as to leave narrow 25 spaces between each edge of the baffle plates and the sides of the drum, as shown in Fig. 3, such spaces being about three-fourths of an inch wide. Through these spaces pass the products of combustion which ascend 30 between the baffle plates where their progress is arrested. The products of combustion continue to ascend to the space above the second or upper baffle plate 24 and are arrested by the baffle plate 26 which extends across the drum on opposite sides 35 thereof and is mounted on one edge at the top of sheet metal support 27 secured at its lower end to the rear wall 3' of the drum. The opposite edge of the baffle plate 26 40 terminates at a short distance from the front wall 4 of the drum, thus permitting the products of combustion to pass to the space above the baffle plate 26 between the latter and the top of the drum 3. The products 45 of combustion pass through this passage way to the rear and into the descending passage way 28 formed by the vertical plate of sheet metal 27 and the rear wall 3' of the drum and down to the bottom of said passage way 50 and out through two passage ways 29 connecting the rear wall 3' of the drum with

a vertical passage way 30 communicating at its upper end with a horizontal passage way 32 through which the products of combustion escape after they have passed up 55 through the vertical passage way 30.

The location of the baffle plates is such that the products of combustion are at all times forced to the outer portion of the radiator or drum whence the heat is radiated 60 into the air in the space surrounding the drum. The passage way 30 through which the products of combustion ascend also causes the heat to be radiated to the outer portion of the drum losing still more of its 65 heat into the surrounding air. Still more of the heat of the products of combustion passes into the air space surrounding the drum. All the joints and seams are double and are packed with asbestos so constructed 70 that in no possible way can any of the gas, or fumes of the products of combustion escape from the drum into the surrounding air space or into the room it is desired to heat. The air in the spaces surrounding the 75 drum is thus heated by the radiation from the drum and is confined by the casing and having no other way to escape passes through the passages 10 in the top of the casing to the room to be heated. 80

Having described our invention, we claim:—

A furnace comprising a casing, a fire box within said casing and spaced from the walls thereof, a baffle plate in said fire box 85 extending from a point adjacent the top of said fire box and forming therewith a shallow descending passageway 28 extending across one side of said fire box, a vertical passageway 30, a discharge pipe 32 communicating therewith and a pair of pipes 29 providing communication between the lower end of said shallow passageway 28 and said vertical passageway 30. 90

In testimony whereof we hereunto affix 95 our signatures in presence of two witnesses.

GEORGE H. MINIER.
THADDEUS LOWE.
